(57) **CLAIM**

The ornamental design for a rectangular fluted stackable container, as shown and described.

DESCRIPTION

FIG. 1 is a top perspective view of the container;
FIG. 2 is a top perspective view of the lid for the container shown separately for clarity;
FIG. 3 is a left side view of the lid for the container, the right side view being a mirror image, shown separately for clarity;
FIG. 4 is a front view of the lid for the container, the rear view being a mirror image, shown separately for clarity;
FIG. 5 is a top plan view of the lid for the container shown separately for clarity;
FIG. 6 is a bottom plan view of the lid for the container shown separately for clarity;
FIG. 7 is a top perspective view of the base for the container shown separately for clarity;
FIG. 8 is a left side view of the lid for the container, the right side view being a mirror image, shown separately for clarity;
FIG. 9 is a front view of the base for the container, the rear view being a mirror image, shown separately for clarity;
FIG. 10 is a top plan view of the base for the container shown separately for clarity; and,
FIG. 11 is a bottom plan view of the base for the container shown separately for clarity.
